Leonard D. Cherneff, Seattle, Wash.

Application November 13, 1945, Serial No. 123,720

Term of patent 14 years

(Cl. D29—23)

To all whom it may concern:

Be it known that I, Leonard D. Cherneff, a citizen of the United States, residing at Seattle, in the county of King and State of Washington, have invented a new, original, and ornamental Design for an Altar or Similar Article, of which the following is a specification, reference being had to the accompanying drawing, forming part thereof.

In the drawing

Fig. 1 is a front elevation of an altar or similar article showing my new design.

Fig. 2 is a top plan view of the same.

Fig. 3 is a side elevation of the same.

I claim:

The ornamental design for an altar or similar article, as shown.

LEONARD D. CHERNEFF.
